George C. Ring
HEIR ATTORNEY

UNITED STATES PATENT OFFICE.

ALEXANDER C. BROWN AND HARRY GILLETT, OF CLEVELAND, OHIO; SAID BROWN AS-
SIGNOR TO THE BROWN HOISTING MACHINERY COMPANY, OF CLEVELAND, OHIO,
A CORPORATION.

BUILDING SECTION.

Application filed June 3, 1921. Serial No. 474,733.

To all whom it may concern:

Be it known that we, ALEXANDER C. BROWN and HARRY GILLETT, citizens of the United States, residing at Cleveland, in the county of Cuyahoga and State of Ohio, have invented a new and useful Improvement in Building Sections, of which the following is a full, clear, and exact description, reference being had to the drawings accompanying and a part of the specification, wherein similar parts are designated by similar numerals in each case.

Our invention relates more particularly to that class of constructions, like roofs, walls, and flooring, which require as a main component or element, a preformed building section, that combines, in marked proportions, the qualities of rigidity, strength, and insulation, with a minimum of weight, mass, and placement operations. It is the purpose and object of the present invention therefore to provide a special preparation or composite, of the nature above referred to that will meet all requirements, and in an exceptional degree.

We accomplish this object by a unitary article, which, broadly speaking, consists of a body portion of cork mastic compressed and molded into a slab like section, around a central reinforcing form or sheeting which, except as specially explained herein, is substantially equidimensional with said body portion itself and the component half portions that characterize the same.

In the accompanying drawings, Figure 1, is a plan view of a slab or board, representing said invention, the dotted lines in the same indicating the side edges of the centrally placed reinforcing material. Figure 2 is an enlarged view of a portion of the end of the slab. Figure 3 is a vertical sectional view on the lines 8—8 of Figure 1; Figure 4 is a developed view of a slab such as appears in Figure 2, when the reinforcing material is perforated; Figure 5 is a special form of a section when the reinforcing material is of a kind and is exposed in a manner to permit of the ends and sides interlocking with similar exposed portions of contiguous sections. Figure 6 is an enlarged broken view of the end of the board shown in Figure 5, and Figure 7, a perspective view of a plurality of the boards in a roof, or other formation.

The reinforcing element may be of any

suitable material or form, such as plate, wire-mesh, expanded or corrugated metal, or latticed wood, that has a positive or plus quality of rigidity and strength. The various kinds of corrugated metal will be preferred for the purpose, and, of these, the so-called ferroinclave form of sheet metal, as set forth in United States Letters Patent 689281, showing corrugations with claviform or dovetailed cross-sections, has distinct advantages in this and other respects in the connection, and is made the basis of a special claim accordingly.

Where plate, or forms of metal other than dovetailed are used for said element, special provision should be made for securing the mastic element in place around the same, either by connecting the mastic portions of said element directly to the faces of the reinforcing element with which they are in contact, or to each other.

A provision for the latter alternative, is illustrated in Figures 2 and 4. It is applicable when plate is used, or material having corrugations with other than dovetailed cross-sections.

Whatever form of reinforcing element is selected, it will substantially conform, in superficial dimensions, or shape to the predetermined form of the finished section, and, in the process of compressing and molding the cork-mastic about the same, said element is to be so arranged and handled that, in the final result, it will be centrally related to said section. This requirement will be readily understood by those practiced in the art, and need not be further set forth here, as is likewise the case with respect to the various stages and requirements of the process itself. As to the latter operation, it is expected, of course, that the union of the cork member around the reinforcing member, in order to form said section, will be brought about by the firm compression of the same into molds containing said reinforcing member in such manner and under such physical and other conditions that said mastic will be forced into the dovetailed corrugations when ferroinclave is used, or through, or into said perforations or other connection provision, where other material is used for the reinforcing member, in order to thereby lastingly bond and compact said elements together.

In said drawings, A, Fig. 1, is a full view

of a primary form of the completed article and section. In such form the plane portions of the cork envelope 15, around the reinforcing central member of said article, 5 are equidimensional, one with the other, and substantially with the member they enclose. The dotted lines in said figure indicate the side edges of said embedded member.

In Figs. 5 and 6, as a special form of the 10 invention, the covering layers of cork, 16 and 17, corresponding with the plane portions, or layers 15 in Fig. 1, are not in contact with each other at all, but are made to occupy oppositely related and smaller areas 15 on the reinforcing member than as shown in Fig. 1. This form may be produced from the sectional form shown in Fig. 1 by removing equidimensional rectangular strips of the cork covering 15, from and along 20 alternate ends and sides of the two faces, to such an extent as will expose oppositely related portions of the central reinforcing medium, and adapt the same to be brought into bearing with correspondingly exposed 25 parts of similar sections.

In Figures 5, 6 and 7, for instance, as will be seen, by reason of making the mastic layers rectangular and smaller than the central sheet or member 14 in the manner 30 described, they will be located at opposite corners or angles of the faces of said member, with two adjacent edges coincident with two adjacent and opposite edges of the member in each case, and the latter, because of 35 its larger area or size, will extend beyond the layers, and be exposed as strip-like portions 16^a and 16^b, along the top and right hand side of the upper face of the member, and 17^a and 17^b, along the bottom and left 40 hand side of the other or under face, while the layers themselves, will severally cover the remaining portions of the sheet member in opposite and reversed relations to the same and to each other. It accordingly fol- 45 lows that the exposed strip-like portions 16^a and 16^b, and 17^a and 17^b, and the edges of the layers adjacent thereto, in a finished section, will always compose or form a re- 50 cess or rabbet along the sides and edges of the section, that will usefully interlock and 55 engage with the corresponding recesses in similar sections, when such are brought together in a given construction for the purpose. The width of the strip-like portions referred to, will, of course, depend upon 60 the requirements of each case. (See Fig. 2.)

The edges of the layers along said lines should be squared and be even with the edges of the sheet, and, when a ferroinclave 65 sheet is used as 14, in Fig. 6, it will be ob- 60 vious that the sheet should be so calculated as to terminate at the sides with the horizontal member of a corrugation.

When said section A, or said modified 70 form thereof, B, is made up as described,

the resulting product will present a building material that is ready for shipment in a form for immediate use at the site of erection, whereby the delay, loss and cost of separate handlings of the essential components of the same, are avoided or largely reduced. In the secondary form of the invention (see Figs. 5 and 6), by reason of the union of the particular constituents in the special manner illustrated, all the advantages of scarfed and overlapping joints, in assembling the sections in a given structure, are obtained without the coefficient of weakness that characterizes structural unions of that kind, where the material parts involved must first be reduced in order to fit together in a level joint.

Although cork and cork mastic are used in the foregoing description, it is to be understood that we do not intend to limit 85 our invention to a strict definition of those terms, but wish the same to be construed as equally comprising any and all chemical mixtures and combinations having cork wood as the main ingredient.

Having thus described our invention, that which we claim, and wish to protect by Letters Patent, is the following:

1. As a component of roofs and similar constructions, a preformed building section 95 comprising the combination of a rectangular stiffening member, a rectangular layer of cork mastic so located on and with respect to one face of said member that two adjacent edges of the same coincide with two adjacent edges of the stiffening member, a rectangular layer of cork mastic of the same size as the first named layer, so located on and with respect to the other face of said member that corresponding edges of the same coincide 100 with two other adjacent edges of the stiffening member, said layers being of equal dimensions one with the other, and of such size with respect to said faces, that, when in their described places thereon, the exposed faces 105 and the edges of the layers adjoining the same, will together form rabbeted recesses for interlocking engagements with corresponding recesses in similar building sections 110 when brought together for the purpose.

2. As an article of manufacture, the combination of a corrugated rectangular sheet member, a smaller rectangular layer of cork mastic on one face thereof so located with respect to such face that two adjacent edges of the same coincide with two adjacent edges of the sheet member, a rectangular layer of cork mastic of the same size as the first named layer on the other face thereof, so located with respect to such face, that corresponding edges of such layer coincide with the two adjacent edges of said member opposite to the first named adjacent edges thereof, the superficial dimensions of said layers being so proportioned with respect to 115 120 125 130

- the superficial dimensions of said member, that, when in their described places relative to each other, the exposed faces of said member and the edges of the layers severally adjoining the same, will together form rabbeted recesses in the section for interlocking engagements with corresponding recesses in similar building sections when brought together for the purpose.
3. A preformed building section, comprising the combination of a rectangular ferroinclave stiffening member, a rectangular layer of cork mastic of lesser superficial dimensions than said member in firm contact with one face thereof, with two adjacent edges of the layer coincident with two adjacent edges of the member, a rectangular layer of cork mastic, of the same dimensions as the first named layer, in similar contact with the other face of said member, with corresponding edges of the same coincident with the two adjacent edges of said member opposite to the first named adjacent edges thereof, the size of said layers being so proportioned with respect to the size of said member, that, when in their described places relative to each other, the exposed faces of the member and the edges of the layer severally adjoining the same, will together form rabbeted recesses in the section suitable for interlocking engagements with corresponding recesses in similar building sections when brought together for the purpose, substantially as shown and described.
4. As an article of manufacture, a preformed building section, comprising the combination, with a rectangular strengthening member, of a rectangular layer of cork mastic of smaller superficial dimensions on one side of the same with two adjacent edges coincident with two adjacent edges of the member, a rectangular layer of cork mastic equidimensional with the first named layer, on the other side of the member with its corresponding edges coincident with two adjacent edges of said member opposite to the first named edges of the member, the size of said layers being so proportioned with respect to the size of said member, that when in their described places relative to each other, the exposed faces of the member and the edges of the layers severally adjoining the same, will together constitute rabbeted recesses in the section suitable for interlocking engagements with corresponding recesses in similar building sections when brought together for the purpose, substantially as shown and described.
